UNITED STATES PATENT OFFICE.

LEGER J. CASTONGUAY, OF HARRISBURG, PENNSYLVANIA.

PLUG-SOCKET.

1,091,562.

Specification of Letters Patent. Patented Mar. 31, 1914.

Application filed February 1, 1911. Serial No. 605,950.

To all whom it may concern:

Be it known that I, LEGER J. CASTONGUAY, a subject of the King of Great Britain, residing at Harrisburg, in the county of Dauphin and State of Pennsylvania, have invented new and useful Improvements in Plug-Sockets, of which the following is a specification.

The present invention relates more particularly to plug sockets of the type employed for holding incandescent lamps and the like, and one of the primary and important objects of the present invention is to provide a novel and practical structure, whereby the two sections of the usual shell may be secured together in different positions so as to afford convenience in wiring, and in order to place the key in the most desirable or convenient position.

A further and important object is to provide novel and simple electrical connections and switch mechanism that can be assembled with ease and expedition, and is also readily accessible. The structure moreover is such that the insulator members can, if desired, be molded directly in the shell sections or elements.

A simple embodiment of the invention is illustrated in the accompanying drawings and is described in the following specification, but it will be evident from an inspection of the claims hereto appended that the structure disclosed, is open to various changes and modifications.

In said drawings, Figure 1 is a longitudinal sectional view through the socket, showing the parts in assembled position. Fig. 2 is a sectional view on the line 2--2 of Fig. 1. Fig. 3 is a bottom plan view of the upper insulator member. Fig. 4 is a sectional view substantially on the line 4--4 of Fig. 2. Fig. 5 are detail views of the make and break device. Fig. 6 is a side elevation of the securing yoke. Fig. 7 is a top plan view of the same. Fig. 8 is a detail sectional view, illustrating the manner in which the yoke is employed to secure the shell elements together. Fig. 9 is a top plan view of the socket.

Similar reference numerals designate corresponding parts in all the figures of the drawings.

In the embodiment disclosed, the shell consists of a cap element 10 and a body ele-

ment 11, the two detachably interfiting with 55 the upper end of the body element 11 located within and rotatable with respect to the cap element 10. The said cap element is provided with a central opening 12, through which passes a bushing 13, the inner end of 60 said bushing being suitably flared, as shown at 14, and thereby holding in place a washer or collar 15. The said cap element furthermore is provided with an annular series of 65 inwardly extending indented teeth 16.

A yoke, designated as a whole by the reference numeral 17, and shown in detail in Figs. 6 and 7, is rotatably mounted within the cap element 10, said yoke consisting of a central circular washer portion 18 that is 70 rotatable upon the collar 15, and said washer has a pair of downwardly and outwardly extending arms 19 provided with terminal enlargements 20 that rest upon an inturned flange 21 formed at the lower edge of the 75 cap element 10. These arms are provided with sockets 22 that are arranged to engage or receive certain of the teeth 16 of the cap element, and thus it will be evident that this yoke will be held against rotation with respect to the cap element and in different positions with relation thereto. In order that the arms may be readily disengaged from the teeth 16, they are provided with depending finger pieces 23 that extend below the 80 cap, and are entirely accessible when the shell element 11 is removed. The said shell element 11 is provided on one side with the usual key-receiving slot 24, and on the opposite side has two openings 25 that are 85 shown as circular, though the configuration of the same is immaterial. These openings detachably receive a pair of inset lips 26 formed upon one of the heads 20. The opposite head is provided with corresponding 90 lips, one of which is engaged in a similar opening 25 located outside the key socket 24.

With the above construction, it will be evident that the body element 11 of the shell will be effectively though detachably secured to the cap element 10, through the medium of the yoke 17, and inasmuch as this yoke can be rotatably shifted to different positions, the body element can be arranged in different positions with respect to the cap element, thereby placing the key in different positions with respect to the cap, and also making it more convenient for wiring.

It will of course be understood that the adjustment of the yoke must be made prior to the application of the body element 11. The said yoke, as shown in Figs. 7 and 9, is provided with a pair of outstanding ears 27, and to these ears, are secured by screws 28, an upper insulator member 29 that is thus rotatable with the yoke. It will be noted that this insulator member is located wholly within the cap. It is provided with a central opening 30, and secured to its under side, by binding screws 31 and 32, as shown in Fig. 3, are a pair of wire terminal plates 33 and 34 that are also fastened by screws 35 passing downwardly through the insulator member 29. A conductor spring 36 has one end bent around and secured behind the plate 33.

A lower insulator member 37 is located within the body element 11 of the shell, and secured within the same is a side plug contact 38 preferably in the form of a screw having an inturned flange 39 secured in place by a continuous circular washer 40 that surrounds a boss 41. The washer 40 is held in place by a pair of screws 42 which pass upwardly through the insulator member 37, and secure a conductor plate 43 and a bracket 44 to the top of the same, as shown in Fig. 2. Operating between the conductor spring 36 and the plate 43 is a make and break device 45, shown in detail in Fig. 5, which preferably consists of an angular boxing having one side open and provided with an orifice 46 in the central portion of its opposite side. This device, when turned to a vertical position, will electrically connect the spring 36 and plate 43, but when moved to a horizontal position, will be out of engagement with the part 36. The bracket 44 is provided with a pair of spaced ears 47, in which is journaled a spring shaft 48 that is fixed to the usual key 49. This shaft 48 is preferably made of tempered wire, and is rotatable in the orifice 46, its rotatable movement with respect to the make and break device 45 being limited however, inasmuch as its end is formed into a hook 50 constituting a head that is arranged within the cavity of the make and break device, said head engaging the opposite walls when the key 49 and shaft 48 are turned a predetermined distance. The arrangement is such that when the make and break device 45 is electrically connecting the elements 36 and 43, as shown in Fig. 1, lateral tension will be placed upon said shaft, and thus when the shaft is turned sufficiently to rotate the make and break device 45 and carry the latter past its dead center, the tension on said shaft will cause a sudden movement of the device 45 to a horizontal position, and at the same time, will carry it down so that it will rest flat upon the plate 43, thus making a quick break. On the other hand, when the key is turned to

move the device 45 to the position shown in Fig. 1, it will be a gradual movement until the position illustrated is reached.

A center plug contact 50^a is employed that is preferably in the form of a stud slidably mounted centrally in the insulator member 37 and boss 41, and having at its inner end a stop head 51 that limits its outward movement. This head is borne upon by a substantially S-shaped conducting spring 52, which spring is held beneath the base 53 of a standard 54, secured by a screw 55 to the top or inner end of the insulator member 37. The standard 54 carries another spring 56 that detachably bears against the wire terminal plate 34 or the screw 35 that secures the same in place. With this arrangement, it will be noted that the current conveyed by a wire connected to the binding post 32 will pass through the spring 56, standard 54, spring 52, to the center plug contact 50^a, and the latter will be yieldingly maintained in its outer position by said spring 52 passing through the lamp or other electrical device located in the socket. The current will return through the washer 40, plate 43, make and break device 45, conductor spring 36 and plate 33 to the other binding post 31, thus completing the circuit.

From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

Having thus fully described my invention, what I claim as new, and desire to secure by Letters Patent, is:—

1. In an electric plug socket, the combination with relatively rotatable and detachably associated shell elements, of a securing device rotatably mounted within one of the elements and detachably engaging the other to secure the two elements together.

2. In an electric plug socket, the combination with relatively rotatable and detachably associated shell elements, of a securing device rotatably mounted within one of the elements and detachably engaging the other to secure the two elements together, and means for holding the securing device against its rotary movement and in different positions.

3. In an electric plug socket, the combination with relatively rotatable and detachably associated shell elements, of a securing device rotatably mounted within one of the elements and detachably engaging the other to secure the two elements together, said device detachably interlocking with the element which carries it at a plurality of points to

hold said device against its rotary movement and being rotatable when the shell elements are being disconnected.

4. In an electric plug socket, the combination with a cap element having a plurality of teeth, of a securing yoke rotatably mounted on the cap element and having a socket that receives different teeth to hold the yoke and cap element against relative movement and in different positions, and a body element that is detachably engaged by the yoke and is thereby held to the cap element in different positions with respect thereto.

5. In an electric plug socket, the combination with a cap element, of a spring arm rotatably mounted therein, and detachably interlocking with the cap element at different points to prevent its rotation, and a body element that detachably engages with said arm.

6. In an electric plug socket, the combination with a cap element, of a spring yoke journaled within the same and having arms that detachably interlock with the cap element at different points to hold the yoke against rotation and in different positions, and a body element that detachably engages with said arms of the yoke.

7. In an electric plug socket, the combination with a cap element having a plurality of inset teeth, of a bushing carried by the cap element, a yoke rotatably mounted on the bushing and having depending spring arms provided with sockets that receive the different teeth, to hold the yoke against rotation and in different positions, and a shell element that detachably fits within the cap and detachably interlocks with the arms.

8. In an electric plug socket, the combination with separable insulator members having adjacent sides, of a wire terminal carried by the adjacent side of one member, a plug contact movably mounted on the other member and projecting through its adjacent side, and electrically connected springs mounted on the adjacent side of one member and detachably and yieldingly bearing against the wire terminal and the plug contact.

9. In an electric plug socket, the combination with spaced conducting elements, of a make and break device rotatably located between them, an operating key having a laterally flexible shaft that is rotatable in

the make and break device, and is flexed on 55 the movement thereof, and means for limiting the amount of such rotation.

10. In an electric plug socket, the combination with spaced conducting elements, of a make and break device rotatably located 60 between them, an operating key having a laterally flexible shaft that is rotatable in the make and break device and is flexed on the movement thereof, and a head carried by the shaft and engaging the make and 65 break device to cause its movement after a limited independent movement of the key and shaft.

11. In an electric plug socket, the combination with spaced contact elements, of a 70 make and break device rotatably located between them, a key having a spring shaft that is engaged with the device, and a bearing for said shaft, the make and break device when in a predetermined position causing 75 the shaft to be laterally flexed.

12. In an electric plug socket, the combination with spaced separable insulator members, of conducting elements carried thereby and spaced apart, a box shaped make 80 and break device rotatably located between the elements, a key having a spring shaft fixed thereto, said shaft being rotatably engaged with the make and break device, a 85 head carried by the shaft, and located within the make and break device, said head having a limited movement with respect thereto, and a bearing for the spring shaft, said shaft being laterally flexed when the make and 90 break device is in a position to electrically connect the conducting elements.

13. In electric light sockets, the combination of a cap, a rotatable member carried by the cap and provided with one or more depending locking spring arms, a shell 95 to coöperate with the cap having one or more openings between its ends for the reception of a portion of the spring arms so that they may be readily operated to disengage the cap and ring.

In testimony whereof I have hereunto set my hand in presence of two subscribing witnesses.
